John Monson
INVENTOR.

UNITED STATES PATENT OFFICE.

JÖNS MONSON, OF NEW YORK, N. Y.

SPINNING TOY.

Application filed June 11, 1928. Serial No. 284,432.

This invention relates to amusement and pastime games and has reference to spinning toys, and is a continuation in part of my abandoned application, Serial Number 5 171,716, filed Feb. 28, 1927, which discloses the modifications shown in Figures 1 to 8, described below.

The purpose of the invention is to provide a toy that will interest both young and 10 old and will amuse a single person as well as a company.

The toy consists of a flat, hollow and preferably round body with one or both of its two flat sides transparent. It has one spherical ball free in a round cavity with rigid sides. The cavity has fixed resting places for the ball. These resting places consist of hollows or grooves in the sides of the cavity. The side of the cavity on which the ball comes to rest has slope for the ball from 15 every point to some resting place. The cavity may have as many resting places as desired. The ball is spun by giving the toy a ring-like slide or an edge-wise spin on a level surface. The toy may be made with two 20 cavities of which each has a free ball, and it can be made composite with several toys in one body. The toy can also be made with corners on the edge. The shell of the toy 25 may be made in as many parts as desired, and the parts fixed together. The toy has game indicia.

Referring to the accompanying drawings:

Figure 1 is a side elevation of the toy.

Figure 2 is a section in the line 11 of Fig. 35 1, when the toy has its top side transparent and resting places for the ball in the center side of the cavity.

Figure 3 is a view of the bottom side of 40 the cavity, when the toy has its top side transparent and resting places for the ball in the center side of the cavity.

Figure 4 is a section in the line 11 of Fig. 45 1, when the toy has both of its two flat sides transparent and resting places for the ball in the center side of the cavity.

Figure 5 is a section in the line 11 of Fig. 50 1, when the toy has two cavities with one ball in each, and it has both of its two flat sides transparent.

Figure 6 is a view of the ball.

Figure 7 is a section in the line 11 of Fig.

1, when the toy has its top side transparent and resting places for the ball in the bottom side of the cavity. 55

Figure 8 is a view of the bottom side of the cavity, when the toy has the top side transparent and resting places for the ball in the bottom side of the cavity.

Figure 9 is a side elevation of a composite 60 toy with plural number of separate toys in one body.

Figures 10 and 11 are side elevations of the toy with corners on the edge.

In the drawings the same numbers mark 65 the same kind of parts.

Fig. 1 shows the transparent top side of the toy with game indicia. When both the flat sides are transparent, they both show game indicia. 70

Figs. 2 and 3 show the toy with the transparent top side 2, the ball 3, the cavity 4, the bottom part of the toy 5, the grooves in the center side of the cavity 6 and the center part of the toy 7. The grooves in the center 75 side of the cavity are the resting places for the ball. The bottom side of the cavity has slope for the ball from every point to some resting place. When the toy has only the top side transparent, it is operated by giving 80 it a ring-like slide on a level surface.

In Fig. 4 the toy has both its flat sides, 2 and 2, transparent, and both sides in the cavity have slope for the ball from every point to some resting place. When the toy 85 has both of its two flat sides transparent, it is operated by being spun on its edge on a level surface, and it may come to rest on any of its two flat sides.

In Fig. 5 the toy is really two toys in one 90 with the bottom parts, 5, of both as partition between them.

In Figs. 7 and 8 the toy is shown without a center part and has hollows, 8, in the bottom side of the cavity as resting places for 95 the ball.

In Fig. 9 a composite toy is shown with plural number of separate toys in one body all operated at once.

I claim:

1. A spinning toy comprising a flat, hollow and partly transparent body having one spherical ball free in a round cavity with rigid sides, this cavity having fixed resting

places for the ball and slope for the ball from every point of the side on which it comes to rest to some resting place.

2. A spinning toy comprising a flat, hollow and partly transparent body having one spherical ball free in a round cavity with rigid sides, this cavity having fixed resting places for the ball and slope for the ball from

every point of the side on which it comes to rest to some resting place, and the toy having 10 game indicia.

Signed at New York, in the county of New York and State of New York, this 9th day of June, A. D. 1928.

JÖNS MONSON.
